(Cl. D52—6)

Fig. 1

Fig. 2

Fig. 3

FIG. 1 is a perspective view of an X—Y graphical recorder showing our new design;

FIG. 2 is a side elevational view thereof; and

FIG. 3 is a rear elevational view thereof.

The undisclosed side of the X—Y graphical recorder is substantially the same in appearance as the side shown. The essential features of the design reside in the portions shown in full lines.

We claim:

The ornamental design for an X—Y graphical recorder, as shown and described.
